LOCKING DEVICE FOR GATE HINGES OF A
MOTOR-TRUCK BODY

John Robert Armstrong, London, Ontario, Canada

Application August 13, 1949, Serial No. 110,085

6 Claims. (Cl. 292—300)

1

My invention appertains to improvements in locking devices for hingedly connected gates of motor-truck bodies. The ordinary rack employed as an enclosure for the decks of motor-truck bodies is customarily made up of so-called "gates" having stakes engaged in pockets on the truck-body to enable it to be readily detached as occasion may require. A recognized difficulty with gates of such racks is that the stakes occasionally jump out of the pockets when the truck is traveling over rough pavements and roads. Locking devices of one kind or another are resorted to for the purpose of preventing the gates from becoming detached and falling off the truck.

The aim of my invention is to provide an improved mode of locking the hinge connections between adjoining gates, and further to provide a locking device which is simple in construction and which will permit of the gates being quickly freed for removal.

Another object of the invention is to provide a locking device which is inexpensive to manufacture and easy to use.

The locking device of my invention comprehends a ring, loop or like member for engaging on the knuckle and pintle portions of the hinge ordinarily used on a gate of the kind referred to. The ring or like member is made captive to one of the interconnected gates by means of a coil spring placed under tension.

The ring or like member is positioned with a section of a side thereof at the rear of the pintle below the knuckle, and with an opposite section thereof disposed over the knuckle to thereby lock the two leaves of the hinge together. The latter section is provided with a lug which extends inwardly thereof to rearwardly engage the top of the knuckle in order to retain the ring in place.

The invention is illustrated in the accompanying drawing in which:

Fig. 1 is a rear view of a standard motor-truck showing the invention applied to the gates on the body.

Fig. 2 is a fragmentary view of two adjoining gates depicting the locking device applied to the hinge thereon. This view shows how the locking ring is initially placed on the hinge.

Figs. 3 and 4 are views similar to Fig. 2. In Fig. 3 the ring is shown partly turned to bring the lug thereon into engagement with the top portion of the pintle. In Fig. 4 the ring is shown fully turned to engage the lug with the top portion of the pintle.

Fig. 5 is a perspective view of the locking ring.

Fig. 6 is a plan view of the locking device in applied position on the hinge, and

Fig. 7 is a view showing the locking device on a hinge at the corner formed by two gates at right angles to each other. It will be noted that a lug is not used on this ring of the locking device.

2

In the drawing the reference numeral 8 denotes a body of an ordinary motor-truck. Said body is of the type which is equipped with stake pockets 9, Fig. 1. On the body or deck is a plurality of vertical wall sections or gates which compose the rack. Said gates are illustrated as of the open type which are conventionally made up of the stakes 10 and the rails 11. The gates may, however, be of the solid type in which an imperforated wall is provided with stakes. The gates are supported by engagement of the stakes in the pockets.

The adjoining gates at the sides of said body and at the rear end thereof are connected by the usual type of hinge in which the leaves are detachably secured by a knuckle 12 and a pintle 13. The pintle has a shank 14 extending outwardly from its leaf 15 to a bend or top part 16 from where the pintle extends downwardly to engage the hole in the knuckle and to project for some distance below the same, as will be understood by those familiar with this style of hinge. The knuckle is integrated with the leaf 17. It is usual to employ a plurality of such hinges at the meeting ends of adjoining gates, but only one hinge is shown in the drawing at such meeting ends of the gates. It will be understood, however, that the number of hinges employed on the gates is immaterial to the invention.

The locking device of the invention comprehends a metal ring 18 of a size to freely encompass the knuckle 12 of the hinge and the portion of the pintle 13 extending therethrough. Said ring is made substantially elliptical in shape and in its locking position it is arranged lengthwise of the hinge. The top side section 19 and the bottom side section 20 of the ring are curved to one side of a plane containing the ends 21 of the ring. This arcuate shape enables the ring to be placed over the assembled leaves of the hinge with one end of the ring seated against the shank 14 of the pintle and the other end seated against the shank 22 of the knuckle, and with the top side section 19 extending behind the top portion 16 of the pintle and with the bottom side section 20 extending behind the protruding end of the pintle.

In this applied position on the hinge, the locking ring effectively secures the pintle against withdrawal from the knuckle. To maintain the locking ring in applied position, it is provided with an integral lug 23 which projects downwardly from the top side section 19 to rearwardly engage the top 16 of the pintle. The ring is attached by a coil spring 24 to the gate that carries the pintle of the hinge. Said spring has one of its ends permanently fastened to the gate and the other end similarly secured to the ring as by an eye-piece 25. In applied position, the ring is

endwise tensioned by the spring to firmly retain it in place.

To apply the locking ring, it is initially sleeved over the lower end of the pintle and placed over the knuckle, as shown in Fig. 2, at an angle so that the lug may be passed behind the top 16 of the pintle. The ring is then turned to a horizontal position with the lug engaged with the rear face of the pintle-top, see Figs. 3 and 4. The spring is pulled in applying the ring and 10 the tension thereof maintains the ring in place. The locking ring can be easily applied and quickly removed. It provides an effective lock and is inexpensive to manufacture.

It will be noted that in Fig. 7 there is shown 15 a locking ring 26 of a variant form. This locking ring is a plain circular member without a lug. It is used on the gates at the rear corners of the truck-body and is tensioned by the spring 27. Since the leaves of a corner hinge are connected 20 at right angles to each other, the spring pulls in a direction to retain the ring in place.

The advantages and utility of the invention will be manifest from the preceding description, and it will be understood that such incidental changes and modifications of the selected form of the invention may be resorted to as fairly come within the scope of the appended claims.

What I claim is:

1. A locking device for a gate-hinge having 30 separable leaves provided with a knuckle and a pintle loosely extending downwardly through the knuckle and endwise protruding therebelow, said locking device comprising a ring having a bottom side section and a top side section, said ring 35 being suited to be sleeved upwardly over the end of the pintle to embrace the knuckle with said bottom side section disposed below the knuckle and said top side section disposed above the same, and retaining means on said top side section for rearwardly engaging a part of the pintle above the knuckle.

2. A locking device for a gate-hinge having 40 separable leaves provided with a knuckle and a pintle loosely extending downwardly through the knuckle and endwise protruding therebelow, said locking device comprising a ring of substantially an elliptical configuration having end sections, a bottom side section and a top side section, said bottom and top side sections being curved through their length away from a plane containing said end sections, whereby the ring is capable of embracing the knuckle and the pintle when sleeved upwardly over the end of the pintle with said top side section disposed at the rear of the upper part of the pintle, and means on said top side section for rearwardly engaging said upper part of the pintle to retain the ring in place.

3. A locking device for a gate-hinge having 45 separable leaves provided with a knuckle and a pintle loosely extending downwardly through the knuckle and endwise protruding therebelow, said locking device comprising a ring of substantially an elliptical configuration having end sections, a

bottom side section and a top side section, said bottom and top side sections being curved through their length away from a plane containing said end sections, whereby the ring is capable of embracing the knuckle and the pintle when sleeved upwardly over the end of the pintle with said top side section disposed at the rear of the upper part of the pintle, and a lug inwardly extending from said top side section for rearwardly engaging said upper part of the pintle.

4. A locking device for a gate-hinge having separable leaves provided with a knuckle and a pintle loosely extending downwardly through the knuckle and endwise protruding therebelow, said locking device comprising a ring of substantially an elliptical configuration having end sections, a bottom side section and a top side section, said bottom and top side sections being curved through their length away from a plane containing said end sections, whereby the ring is capable of embracing the knuckle and the pintle when sleeved upwardly over the end of the pintle with said top side section disposed at the rear of the upper part of the pintle, means on said top side section of the ring for rearwardly engaging said upper part of the pintle, and tethering means for the ring.

5. A locking device for a gate-hinge having separable leaves provided with a knuckle and a pintle loosely extending downwardly through the knuckle and endwise protruding therebelow, said locking device comprising a ring of substantially an elliptical configuration having end sections, a bottom side section and a top side section, said bottom and top side sections being curved through their length away from a plane containing said end sections, whereby the ring is capable of embracing the knuckle and the pintle when sleeved upwardly over the end of the pintle with said top side section disposed at the rear of the upper part of the pintle, means on said top side section of the ring for rearwardly engaging said upper part of the pintle, and a flexible device for attaching the ring to a relatively fixed support.

6. A locking device for a gate-hinge having separable leaves provided with a knuckle and a pintle loosely extending downwardly through the knuckle and endwise protruding therebelow, said locking device comprising a ring of substantially an elliptical configuration having end sections, a bottom side section and a top side section, said bottom and top side sections being curved through their length away from a plane containing said end sections, whereby the ring is capable of embracing the knuckle and the pintle when sleeved upwardly over the end of the pintle with said top side section disposed at the rear of the upper part of the pintle, means on said top side section of the ring for rearwardly engaging said upper part of the pintle, and a helical coil spring for tethering the ring and for tensioning the same in its locking position.

JOHN ROBERT ARMSTRONG.
